UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

WARDROBE TRUNK.

Application filed September 28, 1925. Serial No. 59,134.

This invention relates to wardrobe trunks and has for one of its principal objects to improve the construction of such trunks, to the end that the number of trimmings required to connect the three sections of the trunk together, may be reduced to a minimum.

As is well known in the art, wardrobe trunks usually comprise three sections, viz, the drawer section, a wardrobe section, hinged thereto, and a top or cover section for the said wardrobe section, which in turn is hinged to the latter in a plane at right angles to the first mentioned hinges. Heretofore a comparatively large number of trunk trimmings have been used to connect these three sections together and special locking means have been employed for locking the wardrobe cover section in addition to the means commonly employed for interlocking the wardrobe section proper, to the drawer section.

The present invention on the other hand contemplates the use of special trimmings which are so designed and constructed as to reduce the number to a minimum and, which at the same time, will effectively interlock the wardrobe cover section with the other sections of the trunk so as to prevent its unintentional opening when the trunk is closed and locked, while at the same time, making it unnecessary to provide a separate or special locking means, for such cover section.

A still further object of the invention is to provide a wardrobe trunk construction which will be relatively simple, comparatively inexpensive to manufacture and more effective in use than those which have been heretofore purposed.

With the above and other objects in view which will appear as the description proceeds, the invention consists in the novel details of construction, and combinations of parts more fully hereinafter described and particularly pointed out in the appended claims.

Referring to the accompanying drawings, in which like reference characters designate like parts in all the views;

Fig. 1 is a top plan view of a wardrobe trunk constructed in accordance with the present invention;

Fig. 2 is a fragmentary perspective view of such a trunk looking at the wardrobe cover section end;

Fig. 3 is a fragmentary elevational view as seen from the left of Fig. 1, showing a portion of the trimmings employed for connecting together the wardrobe and drawer sections and for retaining the wardrobe cover section in place when the trunk is closed;

Fig. 4 is a fragmentary perspective view of one of the trimmings shown in the preceding figures viz, the trimming employed upon the drawer section;

Fig. 5 is a fragmentary vertical sectional view taken approximately on the plane indicated by the line 5—5 of Fig. 3 looking in the direction of the arrows;

Fig. 6 is a view similar to Fig. 3 but looking from the right hand of Fig. 1;

Fig. 7 is a fragmentary sectional view taken approximately on the plane indicated by the line 7—7 of Fig. 6; and

Fig. 8 is an enlarged transverse sectional view through the meeting edges of the trimming members.

Referring more particularly to the said drawings, the numeral 10 indicates generally, the drawer section of a wardrobe trunk which may be constructed in any desired manner and which is provided with the end wall 11 which, when the trunk is stood on end, as it usually is when open, constitutes the top member of the said drawer section. The wardrobe section 12, is hingedly secured at the bottom to the said drawer section in any approved manner, by a suitable hinge or hinges, not shown, while at the top it is similarly secured to the said drawer section by a hinge constituting a portion of the trimmings to be later described. The said wardrobe section has hingedly secured to it, as by the hinges 13, the wardrobe cover section 14, as will be clear from the drawings.

Secured to the end or top wall 11 of the drawer section 10 adjacent its meeting edge with the wardrobe section and extending entirely across the trunk, is a trimming member 15, the ends 16 and 17 of which are turned downwardly as clearly shown in the drawings. The end 16 is provided with the loops 18 rigid therewith and constituting members which are adapted to coact with the companion loop 19 carried by a trimming member 20 secured to the wardrobe section 12, to constitute the top hinge 21 between the drawer and wardrobe sections.

The wardrobe cover section 14 is provided

with the companion trimming member 22 along the edge thereof which is adjacent the edge of the top or cover member 11, the opposite ends 23 and 24 of the said member 22 being also turned down, as shown in the drawings.

The said member 22 is provided along its outer edge with an outwardly flared portion 26 which is adapted to receive behind it, the 10 lip or projection 27 with which the member 15 is provided. As will be clear from Figs. 1 and 2, the parts last described extend throughout the major portion of the length of the members 15 and 22 and they serve as 15 interlocking connections between the top wall or cover member 11 and the wardrobe cover 14 for preventing the pivotal movement of the latter about its hinges 13 when the sections are in the closed positions, shown in 20 the drawing. In other words, the flared portion 26 together with the extreme edge of the wardrobe cover member 14 constitute a pocket which receives the projection 27 of the member 15 to prevent the unintentional 25 opening of the wardrobe section.

To further prevent relative unintentional movement between the trunk sections, a trimming member 28 is provided at the right hand side of the trunk, as viewed in Fig. 1 30 in cooperative relation to the down turned ends 17 and 24 of the members 15 and 22 respectively, the said member 28 being secured to the vertical wall of the wardrobe section 12, as will be clear from Figs. 2 and 35 6. This said member 28 is provided with a pocket 29 adapted to receive a projection 30 carried by the end 17 of the member 15, which connection, as will be readily apparent, will tend to prevent relative lateral 40 movement between the walls of the wardrobe and drawer sections. The said member 28 is also provided with a vertical pocket 31 adapted to receive a projection 32 carried by the down turned end 24 of the member 22, 45 which connection will tend to prevent relative lateral movement between the upper edge of the wardrobe section 12 and the wardrobe cover section 14. This last mentioned movement will likewise be prevented in the opposite sides by reason of the provision of the pocket 33 in the trimming member 20 and the projection 34 carried by the end 23 of the member 22.

The various pockets just described, in a 55 sense serve the purpose of dowel pins in that they form readily separate connections between adjacent sections, which, however, when in their closed or operative positions, tend to prevent relative movement, except in one 60 plane between the two sections which they connect. It will thus be seen that by providing a wardrobe trunk with trimmings such as those above described, that the number of such trimmings may be reduced to a

minimum, while at the same time it will only 65 be necessary to provide a single locking means for interlocking the drawer and wardrobe sections of the trunk, the said trimmings serving to interlock and hold in closed position the wardrobe cover section. 70

While one form of the invention has been illustrated and described, it is obvious that those skilled in the art may vary the details of construction as well as the arrangements of parts, without departing from the spirit 75 of the invention, and therefore, it is not wished to be limited to the above disclosure, except as may be required by the claims.

What is claimed is:

1. In a wardrobe trunk having hinged 80 drawer and wardrobe sections, and a cover member hinged to said wardrobe section, a trimming member extending transversely of said cover section along the entire length of its meeting edge, the edge of said member being flared to provide a pocket; and a companion trimming member extending along the entire length of the meeting edge of the top wall of said drawer section, and provided with a projection adapted to enter said pocket, and to thereby afford a dowel-like connection between said cover and drawer section adapted to prevent movement of said 85 cover section on its hinges when all of said sections are closed, said trimming members presenting relatively low smooth surfaces said last named trimming member being provided with hinge elements constituting a portion of the hinge connection between said 90 drawer and wardrobe sections. 95

2. In a wardrobe trunk having hinged 100 drawer and wardrobe sections, and a cover section hinged to said wardrobe section, a trimming member extending along the entire 105 length of the meeting edge of said cover sections, said member having angularly disposed ends, and the edge of said member being flared outwardly to provide a pocket; a companion trimming member extending along the entire length of the meeting edge 110 of the top wall of said drawer section, said member also having angularly disposed ends, and being provided along its edge with a projection adapted to enter said pocket, thereby affording a dowel-like connection between 115 said cover and drawer sections adapted to prevent movement of said cover section on its hinges when all of said sections are closed said trimming members presenting relatively low smooth surfaces; additional 120 trimming members carried by said wardrobe section adjacent the angularly disposed ends of said first mentioned trimming members; and dowel-like connections between said first and last mentioned trimming members. 125

In testimony whereof, I affix my signature.

JULIUS RITTER, JR.
